UNITED STATES PATENT OFFICE.

JOSEPH A. GROEBLI, OF NEW YORK, N. Y., ASSIGNOR TO THE KURSHEEDT MANUFACTURING COMPANY, OF SAME PLACE.

EMBROIDERING-MACHINE.

SPECIFICATION forming part of Letters Patent No. 593,206, dated November 9, 1897.

Application filed November 10, 1896. Serial No. 611,586. (No model.)

To all whom it may concern:

Be it known that I, JOSEPH A. GROEBLI, a resident of the city, county, and State of New York, have invented certain new and useful 5 Improvements in and Appertaining to Embroidering-Machines, of which the following is a specification.

My invention relates to improvements in and appertaining to embroidery mechanism, and will be understood by referring to the accompanying drawings, forming part hereof, to which reference is hereby made.

In the drawings, Figure 1 is a broken-away elevation of so much of an embroidery-machine as will serve and suffice to illustrate my invention. Fig. 2 is a side elevation thereof. Fig. 3 is a front elevation of so much of an embroidery-machine as will serve and suffice to illustrate another form of my invention. Fig. 4 is a broken-away elevation of the upper portion of the left-hand end of the embroidery-machine and exhibits the spring counterbalancing mechanism and compensating mechanism therefor shown in said Fig. 3.

Fig. 5 is a broken-away horizontal section, on an enlarged scale, taken on line 5 of Fig. 4 and showing in detail the shiftable clutch mechanism, as will be hereinafter set forth. The direction of this view is upward, as indicated 20 by the arrow in Fig. 4. Fig. 6 is an end view of Fig. 4, looking from the right of Fig. 4 in the direction of the arrow. Fig. 7 is a broken-away detail face view of one member of the clutch, the section through the clutch to enable such a view to be had being taken through line 7 7 of Fig. 5, the arrow showing the direction of view; and Fig. 8 is a face view of another member of the clutch mechanism, showing also the laterally-moving clutching 30 member. The section through the shaft in this figure is taken on line 8 8 of Fig. 5, the direction of view being toward the left of said figure, as indicated by the arrow.

The object of my invention is to provide a 45 mechanism which shall so support and balance the fabric-frame of an embroidery-machine that the motion of the said frame shall be the same and in the same direction over all parts of the said frame.

It is well known that as at present constructed embroidery-frames, although mechanism

has been provided to balance them, are not properly balanced and the motion of the portions of the frame remote from the point where the pantograph or the jacquard mechanism is attached are not the same in direction or extent as the motions of the part of the frame adjacent to the point of attachment of the jacquard mechanism. By my invention I obviate these defects, and have produced an absolutely parallel motion throughout the entire extent of the fabric-frame, by which means the figures embroidered upon the fabric at a distance from the point of attachment of the jacquard device or pantograph are of the same size and shape as those near to the said point of attachment instead of being, as at present, of different sizes and distorted shapes.

To the ends named my invention consists in the construction and arrangement of devices hereinafter set forth and claimed.

In the drawings, A represents the fabric-frame of an embroidery-machine which may be connected to a pantograph or jacquard mechanism at any suitable point. Stretched upon the fabric-frame is a fabric B, with which coöperate the usual needle-carrying bars C D.

E is the frame of the machine, which frame is shown as provided with brackets F G for the support of the fabric-frame. Pivoted at the point f on the bracket F of the frame is a lever H, which is shown in the present instance as an elbow or bell-crank lever. Pivoted at the point g on the bracket G is a similar lever I. The fabric-frame A is suspended from these two fabric-frame-supporting devices, as follows: Depending from one end h (see Fig. 3) of the lever H and pivoted thereto at the point h is a vertical link or suspension bar or rod J, which is pivoted at its lower end to a bracket K on the fabric-frame, and depending from one end i (see Fig. 3) of the lever I and pivoted thereto at the point i is a vertical link or suspension-bar L, which is pivoted at its lower end to a bracket M on the fabric-frame. The end h' of the lever H (see Fig. 1) is pivotally connected to a longitudinal connecting link or rod N, which extends to the end i' (see Fig. 1) of the lever I and is there pivotally connected to the lever I, so that the levers H and I, with their con-

necting-rod N, constitute a parallel motion, all of whose parts are positively connected together, as by pivots, as shown, so that there will be no lost motion, as in the present type 5 of machine, wherein the fabric-frame is suspended upon rails carried by brackets connected to the fabric-frame and resting upon wheels upon the suspension device. This parallel-motion suspension device may be provided with a counterbalancing device, which is shown in Figs. 1 and 2 as a counterbalancing-weight O for counterbalancing the weight of the fabric-frame and the parallel motion, which weight O is carried upon a lever o, connected to or made integral with the lever H. By virtue of this parallel motion and counterbalancing mechanism it will be obvious that the fabric-frame is supported in a very positive manner, so that a movement of 10 one end thereof will be faithfully reproduced at the other end, so that where a multiplicity of similar figures are intended to be worked by the needles, as is usually the case, the figures will in truth be similar and not more and 15 more distorted as we proceed along the fabric-frame away from its point of connection with the jacquard mechanism.

It is obvious that the fabric-frame and parallel motion may be counterbalanced otherwise than by a weight—as, for instance, by a spring or tension mechanism. One form of this spring or tension mechanism combined with a fabric-frame of the embroidering-machine and the parallel motion is shown in 20 Figs. 3 to 8.

In Fig. 3 the supporting and parallel-motion mechanism are shown as in all respects similar to the corresponding elements in Figs. 1 and 2, with the exception, however, that 25 the weight O and lever o are dispensed with and their place supplied by a counterbalancing-spring or tension device comprised in part by springs P P' and provided with compensating mechanism, as will be explained. The construction and connection of these 30 springs will clearly appear by reference to Figs. 3, 4, and 6. In these figures the frame E of the embroidering-machine is shown as provided at the upper left-hand corner with a journal or pivot socket Q. Swinging freely 35 in this journal or pivot socket Q is a yoke R, which is provided with a rounded face or portion S, which is seated in the journal or pivot socket Q and has extending therefrom a bracket T, provided with an extension t. The yoke R, bearing or socket Q, rounded 40 portion S, and bracket T are pierced for the passage of a shaft U. One end of each of the springs P P' is connected to the bracket 45 T and the other ends of the said springs are connected by means of adjusting-screws v to a cross-head V, (seen clearly in Figs. 4 and 6,) which cross-head is shown as provided with guideways v'. Connected to the extension t of the bracket T and working in guideways v' of the cross-head V is a T-shaped 50 guide or guide-bar W, (clearly seen in Figs.

4, 5, and 6,) which guide-bar prevents the cross-head V from rotating or twisting. The shaft U, which passes through the yoke and its adjunctive devices, is screw-threaded for a portion of its length and carries upon the said screw-threaded portion a threaded nut X, to which the lower end h' of the lever H of Figs. 3 and 4 is shown as pivoted. The end u of the shaft U is shown in Fig. 4 as seated in a cup or socket Y, which is provided with a concave bearing-face y, which bears upon a small circular bulge v², carried by the cross-head V. It will thus be seen that as the yoke is held stationary and the end of the shaft U bears against the cross-head that motion of the fabric-frame will cause the springs P P' to be extended or collapsed, as the case may be, and consequently that the device thus constituted will be a counterbalancing device for the fabric-frame, subserving the same functions as the weighted lever shown in Figs. 1 and 2.

For small motions of the frame the springs are quite efficient and serve the purpose with great exactness. It has been observed, however, that when the fabric-frame is given a greater range of movement and the springs become extended it becomes more and more difficult to extend them farther, and consequently some compensation must be made,

which compensation should be proportional to the extent of movement of the frame, so that the resistance to the movement of the frame will not increase as the frame is given a greater range of movement, but will at all times be substantially the same. For this purpose I have provided a compensating mechanism for automatically controlling the tension of the counterbalancing-spring, one form of which compensating mechanism is shown in Figs. 3 to 8, which I will now proceed to describe. In these figures I have shown a plurality of clutch members a b. The clutch member a is provided interiorly with a series of teeth a' and is mounted upon or made integral with a sleeve a², which is carried loosely upon the shaft U. This sleeve a² is circumferentially grooved at a³ for the reception of the edge of a guiding-disk a⁴, which is carried upon an arbor a⁵ and pressed outwardly on the said arbor by a spring a⁶, so that the clutch member a may have a slight longitudinal movement on the shaft U and will be restored to position by the restoring-spring a⁶. The clutch member b is similarly provided interiorly with teeth b' and, as in the case of the clutch member a, is mounted upon or integral with a sleeve b², which turns freely upon the shaft U and is provided with a circumferential groove b³ for the reception of a guiding-roller b⁴, which is carried upon an arbor b⁵, fixed in the yoke and pressed outwardly by a restoring-spring b⁶, so that the clutch member b may have a longitudinal movement on the shaft U. These clutch members a b are rotated in opposite directions by suitable belts or other means con-

tinuously or periodically. Keyed or otherwise secured upon the shaft U is a clutching disk or member Z, (clearly shown in section in Fig. 5 and in face view in Fig. 8,) which 5 clutching member or disk Z is provided peripherally with projecting teeth z, which enter between the teeth a' and b' of the clutch members a or b, as the case may be, it being noted that the lever H, when the fabric- 10 frame is moved, imparts a longitudinal movement to the shaft U, carrying with it the clutching member or disk Z and engaging the said clutching member with one or the other of the interiorly-toothed clutch members ab.

15 By reference to Figs. 7 and 8 it will be observed that the faces of the teeth a' and b' are wedge-shaped and that the said wedge or inclined faces of the teeth a' b' are inclined in opposite directions, so that the sides of the 20 teeth z of the clutching member Z may abut firmly against an abutting-face of the teeth a' b', so that the inclined faces of the teeth a' b' will guide the teeth z, which are lozenge-shaped, into position and will form a butt or 25 shoulder for the teeth z to bear against.

The operation of this form of my invention will be obvious from the foregoing description. I would state, however, that when any considerable motion of the fabric-frame takes 30 place the counterbalancing - springs are stretched or allowed to contract, and as their tension varies with their degree of distension such variation must be compensated for, which is performed automatically by the 35 movement of the rod U, which brings the clutching member Z of the clutch into engagement with one or the other of the oppositely-rotating clutch members which revolve the shaft U in the nut.

40 What I claim, and desire to secure by Letters Patent, is—

1. In an embroidering-machine, the combination of a fabric-frame combined with means for suspending the same, comprising a plurality of suspension-levers, and a longitudinal connecting-link between the levers for effecting the simultaneous equal movement thereof. 45

2. In an embroidering-machine, the combination of a fabric-frame, a suspension device 50 therefor comprising a parallel-motion device, a spring counterbalancing device for the parallel-motion device and frame, and a compensating mechanism for automatically controlling the tension of the counterbalancing spring, as and for the purposes set forth. 55

3. In an embroidering-machine, the combination of a fabric-frame, counterbalanced supporting devices, vertical links pivoted at both ends suspending the frame from the supporting devices and means for transmitting motion from one supporting device to the other. 60

4. In an embroidering-machine, the combination of a fabric-frame and a parallel-motion supporting mechanism therefor, having all its parts positively connected together, substantially as described. 65

5. In an embroidering-machine, the combination of a fabric-frame and suspension mechanism therefor, a spring counterbalancing mechanism for the said frame and suspension mechanism, and an automatic compensating device for compensating for the irregular tension of the spring mechanism at different periods of its stress. 70

6. In an embroidering-machine, the combination of a fabric-frame, a suspension mechanism, a spring counterbalancing mechanism for the fabric-frame and the suspension mechanism, and an automatic clutch mechanism 80 connected to the spring counterbalancing mechanism during different periods of its stress.

7. In an embroidering-machine, the combination of a fabric-frame, a suspension mechanism therefor, a spring counterbalancing mechanism and a rotating compensating device for compensating for the irregularities of the spring counterbalancing mechanism during different periods of its stress. 85

8. In an embroidering-machine, the combination of a fabric-frame, a suspension mechanism, a spring counterbalancing mechanism and a compensating mechanism for the spring counterbalancing mechanism comprising a 95 plurality of clutch members and a clutching member coöperating with the said clutch members, substantially as described.

9. In an embroidering-machine, the combination of a fabric-frame and suspension device therefor, and a spring counterbalancing mechanism having an automatic spring compensating mechanism therefor, the said spring counterbalancing mechanism and its compensating mechanism being pivotally 105 connected to the frame of the embroidering-machine, substantially as described.

10. In an embroidering-machine, the combination of a fabric-frame, a suspension mechanism therefor, a spring counterbalancing 110 mechanism and an automatic compensating mechanism therefor, the said spring counterbalancing mechanism and compensating mechanism being connected to the embroidering-machine frame so as to move together, 115 substantially as described.

11. The combination of a spring counterbalancing or tension member, a shaft against which the said spring exerts its tension, a nut or bearing upon the said shaft, and means for 120 rotating the said shaft whereby the differences of tension of the spring under different degrees of stress may be compensated for.

12. The combination of springs, a shaft against which the springs exert their tension, 125 a shiftable connection on the said shaft for receiving the thrust of the springs, a clutch device, and a clutching device mounted upon the shaft and adapted for engagement with the clutch device. 130

13. The combination of a spring or tension member, a longitudinally-movable shaft receiving the thrust of the said tension member, a movable bearing on the shaft receiving

the thrust of the shaft, and means for rotating the said shaft to move the bearing thereon so as to compensate for inequalities in the tension of the spring during distension thereof.

5 14. The combination of a spring member, a shaft, a bearing or nut X carried upon the said shaft, a rotating clutch member hung upon the shaft, and a clutching member mounted upon the shaft and adapted for engagement with the clutch member whereby the variations of the tension of the springs during longitudinal movements of the shaft may be compensated for.

15 15. The combination with tension mechanism and a shaft, of a plurality of oppositely-placed clutch members provided with teeth, and a clutching device provided peripherally with projecting teeth adapted for engagement with the teeth of the clutch members, the faces of the teeth of the clutch members being oppositely beveled and the teeth of the clutching member being pointed, substantially as described.

16. A parallel-motion device for fabric-frame of an embroidering-machine, consisting of a plurality of elbow-levers, a longitudinal link connecting the levers for effecting the simultaneous movement thereof, and suspension-links connecting the free arms of the elbow-levers to the fabric-frame. 25

17. A parallel-motion device, fabric-frame of an embroidering-machine and suspension-links pivoted at both ends for connecting the fabric-frame to the parallel-motion device. 30

18. A parallel-motion device for fabric-frame of embroidering-machine, consisting of a plurality of elbow-levers, a longitudinal link for connecting said levers for effecting their simultaneous movement and means for connecting the free arms of the elbow-levers to the fabric-frame. 35
